UNITED STATES PATENT OFFICE

153,885

DESIGN FOR A LIGHT FIXTURE

Jules L. Libby, Elgin, Ill.; Robert I. Burstein, administrator of said Jules L. Libby, deceased, assignor to Libby Engineering Corporation, Elgin, Ill., a corporation of Illinois

Application June 7, 1947, Serial No. 139,522

Term of patent 14 years

(Cl. D48—20)

To all whom it may concern:

Be it known, that I, Jules L. Libby, a citizen of the United States of America residing at Elgin, in the county of Kane and State of Illinois, have invented a new, original, and ornamental Design for a Light Fixture, of which the following is a specification, reference being had to the accompanying drawing, forming part thereof.

Figure 1 is a perspective view of a light fixture showing my new design;

Figure 2 is a front elevational view thereof; and Figure 3 is a top plan view.

I claim:

The ornamental design for a light fixture, as shown.

JULES L. LIBBY.
